(57) **CLAIM**

The ornamental design for thermoinsulation metal encaustic tile, as shown and described.

DESCRIPTION

FIG. 1 is a perspective view of a thermoinsulation metal encaustic tile showing my new design;

FIG. 2 is a front elevational view thereof;

FIG. 3 is a rear elevation view thereof;

FIG. 4 is a top plan view thereof;

FIG. 5 is a bottom plan view thereof;

FIG. 6 is a left side elevational view thereof; and,

FIG. 7 is a right side elevational view thereof.

The claimed design is broken in the center to disclose indeterminate length.
